(57) **CLAIM**

The ornamental design for a waste container cavity, as shown and described.

DESCRIPTION

FIG. 1 is a perspective view of a waste container cavity according to an embodiment of the present invention;

FIG. 2 is a perspective view thereof;

FIG. 3 is a front elevational view thereof;

FIG. 4 is a bottom plan view thereof;

FIG. 5 is a perspective view thereof;

FIG. 6 is another perspective view thereof;

FIG. 7 is another perspective view thereof; and,

FIG. 8 is another perspective view thereof.

The broken line(s) which define the bounds of the claimed design form no part thereof.

1 Claim, 8 Drawing Sheets
